UNITED STATES PATENT OFFICE.

OEL E. WARDNER, OF NEW BRITAIN, CONNECTICUT, ASSIGNOR TO THE TRAUT AND HINE MANUFACTURING COMPANY, OF NEW BRITAIN, CONNECTICUT, A CORPORATION.

ORNAMENTAL NAIL-HOOK.

1,247,912.

Specification of Letters Patent. Patented Nov. 27, 1917.

Application filed May 21, 1913. Serial No. 769,064.

To all whom it may concern:

Be it known that I, OEL E. WARDNER, a citizen of the United States, residing at New Britain, in the county of Hartford and State 5 of Connecticut, have invented certain new and useful Improvements in Ornamental Nail-Hooks, of which the following is a specification.

My invention relates to improvements in 10 ornamental nail hooks, and the object of my improvement is to produce a nail hook having an ornamental head at the front having a hook portion extending laterally from the periphery thereof and having a nail portion 15 fixed to the rear face of the said ornamental head and extending rearwardly therefrom.

In the accompanying drawing:—

Figure 1 is a front elevation of my im- 20 proved ornamental nail hook.

Fig. 2 is a rear elevation of the same.

Fig. 3 is a side elevation of the same.

Fig. 4 is a sectional view on the line $\alpha - \alpha$ of Fig. 1.

My ornamental nail hook comprises a head 10 at the front end which is of ornamental character, which as shown, has a convex front face 11 that is unbroken over the entire surface and has a circular periphery 12 that 25 serves as a base, and a shank 13 integral with the said periphery 12 and extending radially therefrom for an appreciable distance and a hook 14 at the outer end of the said shank 13.

Accordingly, the said ornamental head 10 and hook 14 are integral, and they are 30 formed of sheet metal.

The ornamental head 10 is a shell-like structure, and the rear face 15 thereof is concave.

Secured to the center of the said rear face 15 of the ornamental head 10 is a nail element 16, and which nail element 16 extends axially rearwardly, therefrom.

The said nail element 16 comprises essen- 45 tially an ordinary steel nail, having at the front end a nail head 17.

The manner of securing the said nail element 16 to the said rear face 15 of the ornamental head 10 as shown consists in embed- 50 ding the nail head 17 thereof in an enlargement 18 provided on the said rear face 15.

No claim is made for the particular man-

ner of securing the nail element 16 to the rear face 15, the method shown being preferred, the same being ordinary and well 55 known in other devices than that shown and described.

The nail element being connected to the ornamental head as described permits of the use of a hammer without particular damage 60 to the ornamental head, the front face 11 of which covers the nail head 17 of the nail element.

Accordingly, the ornamental nail hook as 65 described is suitable for having the nail element driven into the wall or wood work of any kind and when so driven the said nail element serves as a firm support for the hook and any articles or devices that are suitable 70 to be placed on the said hook.

The fact that the hook 14 is positioned entirely below the ornamental head 11 permits of the free use of the hammer on the 75 said ornamental head in driving the nail element into the woodwork.

It will be noted that the nail portion of my ornamental nail hook corresponds structurally to the upholsterer's nail of well known form, comprising the ornamental head 11 and the nail element secured thereto, these 80 parts being firmly united to form a rigid unitary structure, the ornamental head being convex and having a continuous and unbroken front wall, the head of the nail element being embedded in the material at the 85 rear side, at the middle, and extending axially rearwardly. The device is constructed suitably to be driven by a hammer, after the manner of the upholsterer's nail, as distinguished from a device of the push-button 90 order, and not adapted for use with a ham- mer.

Thus the correspondence of the nail portion to the upholsterer's nail is essentially 95 complete and unqualified, and the hook 14 is secured to the periphery of the ornamental head and is positioned entirely below the said periphery, suitably to provide clearance for the free use of the hammer in applying the device to the wall or woodwork as de- 100 sired.

The fact that the head portion 17 of the nail element 16 is embedded in the enlargement 18 of the rear wall portion of the

ornamental head 11 permits the front wall of the said ornamental head 11 to be continuous and unbroken, as mentioned.

I claim as my invention:—

- 5 An ornamental nail hook composed of two parts, a nail and a hook, the hook comprising an unmutilated convex head with the nail portion attached to the concave side

and extending axially of the head and a hook integral with the head and sufficiently displaced relatively to the nail head to permit driving of the latter by a hammer.

OEL E. WARDNER.
